133,757

DESIGN FOR A SERVICE WAGON

William Francis Andrick, Detroit, Mich.

Application May 16, 1942, Serial No. 106,918

Term of patent 14 years

To all whom it may concern:

Be it known that I, William Francis Andrick, a citizen of the United States, residing at Detroit, in the county of Wayne and State of Michigan, have invented a new, original, and ornamental Design for a Service Wagon, of which the following is a specification, reference being had to the accompanying drawings, forming part thereof.

Figure 1 is a side elevational view of a service wagon showing my new design.

Figure 2 is a top plan view, and
Figure 3 is a rear elevational view.

I claim:

The ornamental design for a service wagon,
as shown.

WILLIAM FRANCIS ANDRICK.
